UNITED STATES PATENT OFFICE.

STANLEY A. DUVALL, OF CHICAGO, ILLINOIS.

TELEPHONE SYSTEM.

SPECIFICATION forming part of Letters Patent No. 738,780, dated September 15, 1903.

Application filed August 18, 1902. Serial No. 120,066. (No model.)

To all whom it may concern:

Be it known that I, STANLEY A. DUVALL, a citizen of the United States, residing in the city of Chicago, in the county of Cook and State of Illinois, have invented certain new and useful Improvements in Telephone Systems, of which the following is a specification.

My invention relates to telephone systems wherein the lines of subscribers are brought to a central point or points for interconnection, commonly known as "exchange" systems, and particularly to such systems as employ a common source of current-supply at each such central point or station for signaling or talking, or both.

My invention has for its object the simplification of the apparatus at the central office or exchange, the removal of all coils from the talking-circuit, and in general the improvement of the supply and control of the current employed for signaling and for talking.

Heretofore in many of the best systems of which I have knowledge it has been common practice to use what are known as "cut-off" relays, interposed usually in the connections from jacks to main battery and controlling the continuity of the line-circuits from the jacks to the line-relays and to the main battery. Whenever a plug by its insertion in any jack of a line closes the circuit of one of these cut-off relays, the line-circuit is at once and automatically broken or "cut off." I prefer, since contacts in the jacks are a necessity, to utilize them in controlling the line-relays directly without the interposition of any other relays. This is the first improvement. I cause a short circuit around each line-relay coil to be closed whenever a plug is inserted in any jack pertaining to that line.

In order to balance the lines, which is desirable for many reasons, it has been customary to employ separate balancing resistances in one side and the line-relay windings or other relays in the other side. I prefer to divide the windings of the relays and include one-half in each half of the line. This is another improvement.

Heretofore a single main battery has usually been employed—that is, at any given time—for both signaling and talking. In case of accident to this battery it would be quite possible to have an appreciable inter-

ruption of the exchange business before it could be fixed. Then, again, it is often desirable to have different voltages for talking and for signaling, and the expedient has been resorted to of connecting to different points in the same battery. The result of this is to discharge some cells more quickly than others, and when recharging, since they have to be recharged as a collective unit, the partly-discharged cells will be "boiled" while the completely-discharged ones are receiving the necessary charge, working a great injury to the cells. I prefer to connect two batteries in parallel when talking, one being at all times available for signaling and the other for talking. They may be of the same voltage; but in every case if the signaling-battery is more nearly discharged than the other it will receive a charge during connection, and vice versa. The two batteries will reinforce each other in carrying their respective loads.

In common battery systems "supervisory signals" are employed associated with the plug cord-circuits, and the relays controlling these signals are usually placed in the cord conductors, being thus included in the talking-circuits. I prefer to make a bridged connection of my batteries to the cords, with the supervisory relays in the arms of the bridge, so that their impedance is useful to prevent the voice-currents from being repeated into other circuits through the battery connection and is removed from the through talking-circuit with which they are associated.

Many other points will appear to those skilled in the art from a perusal of the following specification, wherein the same reference characters point out the same parts throughout.

Referring to the drawing accompanying this specification and forming a part hereof, the figure is a diagram showing two subscribers' lines connected to their terminal apparatus at a central office, with the connecting-circuits thereat, certain well-known elements, such as the listening and ringing keys, being omitted for the sake of simplicity.

In the figure each line is shown with but a single jack; but it will be understood that this system is particularly applicable to multiple-board work and, in fact, is best adapted

thereto; but as the additional jacks would be the merest duplicates of those shown and simplicity in the diagram is essential they are omitted.

5 A and B are two subscribers' stations connected to the central office by the metallic circuits 1 2 and 3 4, respectively. The apparatus at each subscriber's station is the usual outfit, consisting of a bell or ringer Q, 10 normally connected across in series with a condenser q in such manner that ringing currents from central will find a path, but continuous current from the battery will be excluded. In a normally open bridge are included 15 the telephone-receiver R and the transmitter T, this bridge being closed when the set is in use by means of the switch S, controlled by the receiver in the well-known way. The apparatus at station A being lettered as 20 above, that at station B has the same letters throughout with a prime-point. At the central station the line conductors 1 and 2 are connected, respectively, to the springs j' and j of the spring-jack J through the two windings of the line-relay l. Between the relay 25 windings and the jack-springs the portions 8 and 9 of the line are connected by conductors 7 to the terminals of the signaling-battery B'. Although for convenience of illustration 30 this battery is shown in duplicate, it will be understood that but one such battery is usually employed. The relay when energized pulls up its armature l^{11} to close a local circuit extending from the armature and its 35 contact-point l^{12} through lamp L and to battery B by wires 30.

At each side of the jack J a contact is provided, the one, j' , being connected by conductor 5 to line-wire 2 outside the line-relay 40 l and the other, j^5 , being similarly connected by conductor 6 to line-wire 1. When a plug is inserted in the jack J, the springs j and j' are spread apart to make contact with j^4 j^5 , and the relay is thereby short-circuited or 45 shunted by the conductors 5 and 6, so that it ceases to attract its armature, and the local circuit 30 being broken the lamp L is extinguished.

The connections of line 3 4 are in every 50 way similar to those of line 1 2, the conductors going to relay l' and jack J', having springs j^6 j^8 and short-circuiting contacts j^6 j^8 , connected to wires 3 and 4 by conductors 10 and 11. The line-lamp is L' and the local 55 circuit 31. The connections to the signaling-battery B' are numbered 12.

In order to connect any two lines together, the cord-circuit 17 18 19 20 is provided, having terminal plugs P and P'. The cord conductors are divided by condensers C and C' to separate the two stations from each other conductively, while uniting them inductively, thus insuring separate control of the supervisory signals. Two supervisory signals are provided 60 for each cord, (lettered L^2 and L^3), controlled, respectively, by relays U and U'. A branch wire 28 passes from main feeder-wire

22, connected to one side of main talking-battery B, to the two relays U and U', taking in one winding of each only, and thence by wires 30 70 and 32, respectively, to the two ends 17 and 18 of the cord-circuit on one side. Similarly a branch wire 29 passes from main feeder 21, connected to the other side of battery B, to the other coils of the relays U and U', and 75 thence by wires 31 and 33 to the two ends 19 and 20 of the cord on the other side. By tracing the circuits it will be found that the relays are thus connected serially with the battery across the plug-terminals, the separated windings being of course so directed as to reinforce each other. The relay U controls by its armature u the local circuit 24, 22, B, 21, 25, u , L^2 , thus governing the lamp L^2 , and, similarly, the relay U' controls by its armature u the circuit 26, 22, B, 21, 29, 27, u , L^3 , thus 80 governing lamp L^3 . Included in the circuits 24 and 26 are plug-seat switches p and p' , arranged to be opened by the heels of the plugs when in their seats, so as to keep the lamp- 85 circuits normally incomplete, even when a connection is not made, thus saving battery and also preventing shortening the lives of the lamps, which would follow their constant incandescence. 90

The operation of the system thus described is as follows: When subscriber calls by lifting his receiver from the hook S, current will flow from main battery B' by wire 7 to one winding of relay l, to line-wire 2, transmitter T, receiver 95 R, hook S, line-wire 1, the other winding of the relay l, wire 9, and back to battery. The relay being energized causes the lamp L to receive current over the circuit B, 15, 30, L, l^{12} , l^{11} , 30, 16, back to battery. The operator perceiving the signal inserts answering-plug P, whereby springs j and j' are closed on their back contacts, short-circuiting the relay l through the wires 5 and 6 and retiring the signal. At the same time the switch p has 100 been closed by the removal of the plug from its seat, and the lamp L^2 would light; but the relay U is now receiving current over the circuit B, 21, U, 31, P, j' , wire 6, line-wire 1, subscriber's set S R T, line-wire 2, wire 5, spring 105 j , P, 30, U, 28, 22, and B. This holds up the armature u , and so the lamp is not lighted. Having ascertained the number desired, the plug P' is inserted in jack J', (which is assumed to be connected to that line.) The relay l' will not be energized by this action, because the wires 10 13 and 11 14 are at the 110 same potential. The relay U' does not become energized, and so when the plug-seat switch p' is closed the lamp L^3 lights to indicate that 115 the subscriber B has not answered. When he does answer by taking down his receiver, there is instantly a circuit completed for battery B over the line, as traced for the other line, and the relay U' attracts its armature 120 and extinguishes the lamp L^3 . Either subscriber can attract the attention of the office during a connection by moving his hook, and at the termination of the conversation, when 125

130

both have hung up, both lamps L² and L³ lighting indicate the desire for discontinuation.

Having thus described my invention, what I claim, and desire to secure by Letters Patent of the United States, is—

1. In a telephone system, subscribers' lines, means at each subscriber's station for determining the flow of current in his line, a relay having a portion of its windings connected in one side of the line, and the other portion of its windings connected in the other side of the line, a terminal connective device for the line, and means in the terminal connective device to establish a disabling shunt about each of the portions of the relay - windings when connection is made with the line, substantially as described.

2. In a telephone system, subscribers' lines and terminal connective devices therefor, a relay for each line having its windings connected in the two sides of the line so as to be self-balancing, a source of current-supply, a connection to each side of the line from one side of the said source between the terminal connective device and the relay, and disabling shunt connections for the relay extending from the terminal connective device to the line outside of the relay, and arranged to be closed when connection is made with the line, substantially as described.

3. In a telephone system, a subscriber's line, means at the subscriber's station to determine the flow of current in the line, a signal-magnet connected in the line at the central station, a spring-jack connected to the line in parallel with the signal-magnet connection, normally open contacts in said spring-jack, low-resistance connections from said contacts to points in the line outside the signal-magnet, and means to close said contacts when connection is made with the line, substantially as described.

4. In a telephone system, a subscriber's line, means at the subscriber's station to de-

termine the flow of current in said line, a central station, a spring-jack and a signal-magnet, the spring-jack being normally connected to the line on the inside of the magnet, leaving the magnet between the subscriber and spring-jack, and means to connect the spring-jack to the line outside of the magnet upon making connection with the line, substantially as described.

5. In a telephone system, a metallic talking-circuit extending between two terminal stations, a condenser in each side of said circuit, dividing it into two conductively-discontinuous but inductively - continuous sections, a source of current-supply, a branch connection from each side of the source to both sides of the condenser in the corresponding side of the metallic circuit, and two signal-magnets having divided windings, each with one winding in the branch to one side of one condenser, and the other winding in the branch to the same side of the other condenser, whereby the magnets are bridged across the divided portions of the circuit, with the source in common and between their respective windings, substantially as described.

6. In a telephone system, subscribers' lines, metallic cord - circuits for interconnecting them, signal-magnets for the lines, each cord having its terminals connected through the divided windings of said signal-magnets, so that one-half of each magnet-winding is in each side of the circuit, a source of energy bridged across the said connections between the said magnets, and a condenser connected in shunt around each cord connection with its included windings, substantially as described.

In witness whereof I have hereunto set my hand, this 14th day of August, 1902, in the presence of two witnesses.

STANLEY A. DUVALL.
